UNITED STATES PATENT OFFICE.

JARED B. McLANE, OF READING, MASSACHUSETTS.

METAL-SHEARING MACHINE.

SPECIFICATION forming part of Letters Patent No. 569,226, dated October 13, 1896.

Application filed February 28, 1896. Serial No. 581,202. (No model.)

To all whom it may concern:

Be it known that I, JARED B. McLANE, of Reading, in the county of Middlesex and State of Massachusetts, have invented certain new and useful Improvements in Metal-Shearing Machines, of which the following is a specification.

This invention relates to metal-shearing machines, and has for its object to provide a simple and efficient machine adapted to be operated by hand and to be quickly adjusted for the performance of different kinds of work, or, in other words, changed from the conditions which are most advantageous when heavy pressure is required, as in cutting comparatively thick and heavy pieces, to the conditions which are desirable when lighter pressure is required.

To this end the invention consists in certain novel features of construction and combinations of parts hereinafter described, and particularly pointed out in the appended claims.

Of the accompanying drawings, forming a part of this specification, Figure 1 represents a side elevation of a shearing-machine embodying my invention. Fig. 2 represents an end elevation of the same. Fig. 3 represents a perspective view of a portion of one of the shear-blades. Fig. 4 represents a section on line 4 4 of Fig. 1. Fig. 5 represents a side elevation showing certain additional features. Figs. 6 and 7 represent, respectively, a side view and an end view, showing certain features hereinafter described.

The same letters and numerals of reference indicate the same parts in all the figures.

In the drawings, *a* represents a fixed supporting-frame, and *b* represents a stout lever, one end of which is pivoted at *b'* to ears formed at one end of the frame *a*, said lever extending lengthwise of the frame, its free end being located at the opposite end of the frame from the pivoted end.

c represents a fixed operating member mounted on the frame *a*, said member being, as here shown, a shear-blade.

c' represents a movable operating member secured to the lever *b* and arranged to cooperate with the fixed member *c*.

Each of the members *c c'* in a shearing-machine is preferably composed of a rectangular piece of metal, the angles 2 2 2 2 of which

form interchangeable shearing or cutting edges, either of which may be brought into operative position by suitably changing the position of the said operating member. Said members are inserted in recesses formed for their reception in the frame *a* and lever *b*, and are secured in said recesses by tapered-headed bolts 3, the tapered heads of which engage recesses 4, formed in the ends of the said members. (See Figs. 3 and 4.) A single bolt 3, with its accompanying nut 5, is sufficient to secure one of the said members, the tapering form of the head pressing the member endwise against the opposite end of the recess which receives it. Each member is therefore adapted to be quickly secured and removed.

d represents a cam-head pivoted at *d'* to an ear *d*, formed on the frame *a* and comprising two cams 6 7, either of which is adapted to bear upon the upper edge of the lever *b* at a point near its swinging end.

The head *d* is provided with an operating arm or lever *d'*, which is grasped by the operator, who is thereby enabled to turn the head in either direction and thus force either of the said cams against the lever *b*. The cam 6 has a lesser total rise from the pivot *d'* than the cam 7, its rise being more gradual, so that when the cam is thrown to the extreme of its movements (shown in Fig. 1) it gives the lever *b* a limited downward movement at a comparatively slow rate. The cam 7 has a greater total rise than the cam 6, its rise being more abrupt, so that when the head *d* and its operating-arm *d'* are thrown over to the opposite side of the pivot from that shown in Fig. 1 the cam 7 will give the lever *b* a quicker downward movement than that imparted by the cam 6. Owing to the described form of the cams, the cam 6 is enabled to exert greater power upon the lever *b* and the operating member *c'* than the cam 7, although moving said lever more slowly and through a shorter path. Hence, when comparatively thick heavy metal is to be cut the cam 6 is employed, the muscular force of the operator being enabled to cut a plate or piece of metal that could not be cut by the use of the cam 7, although the operation is necessarily slower. When lighter and thinner pieces are to be cut, the cam-head *d* and its operat-

ing-arm d^2 are reversed to bring the cam 7 into action, this cam giving a more rapid, although less powerful, movement to the lever b and operating member c' . Hence in 5 cutting comparatively-light pieces the operator can work more rapidly than by the use of the cam 6.

The shorter cam of course does not move the lever b to the same extent as the longer 10 cam, and while the latter causes the edge of the blade c' to pass the edge of the blade c throughout the full length of the blades, the former only causes said edges to pass each 15 other through a part of their length, as shown in Fig. 1. This does not, however, affect the operativeness of the machine, for the material intended to be cut by use of the shorter cam is limited in lateral extent, and in order to sever it it is not necessary that the shearing-blades come together throughout their 20 length. In this connection it is to be noted that it is essential to the successful employment of the double-acting cam that the movable cutting member be carried by a lever, for 25 then under different extents of movement of the lever the blades can be caused to cut, the movable blade always starting from the same position and its cutting edge passing that of the fixed blade through greater or less of its 30 length according as the longer or shorter cam is used.

e represents a guard which is secured to the frame a and is arranged to bear upon the upper side of a piece of metal while it is being 35 cut by the operating members and prevent the piece from tipping upwardly, said guard, as here shown, having downwardly-bent ends e' e' , which are secured by bolts e^2 to the frame a . The guard may, however, 40 be of any other suitable construction, and may be applied to the frame in any other suitable way. I prefer to make the guard adjustable, and to this end I have provided additional holes e^3 to receive the bolts e^2 , so 45 that the guard may be raised or lowered on the frame.

To insure operative contact of the blades or operating members c c' with each other, I provide adjustable bearing-plates f , one of 50 which is shown in dotted lines in Fig. 2, said plates being located in recesses in the ear a' and held by set-screws f' against one side of the lever b . The said plate and screws press the plate or member c' on the lever b toward the fixed member c . When the contacting 55 sides of the said blades or members become worn, the wear can be compensated for by setting up the screws f' .

g represents a curved spring-arm which 60 is engaged at one end with a stud g' , affixed by welding or otherwise to the lever b , and at the other end with a stud g^2 , affixed to the cam-head d , and acts to yieldingly hold the lever b in contact with the cam-head, the ends 65 of the spring having a tendency to spring toward each other. By thus supporting the

spring I avoid all resistance by the spring to the downward movement of the lever.

In Fig. 5 I show the lever b provided with an extension b^3 , to the outer end of which is pivoted a lever b^4 , connected by a rod b^5 with a lever b^6 , which is engaged with the cam-head d . The rod b^5 is adjustably connected to the levers b^4 and b^6 , so that it can be set at various distances from the pivots of said levers. The described system of levers enables the operator to exert greater power on the lever b by grasping the lever b^4 . When this extra power is not required, the rod b^5 75 may be disconnected and the cam-head operated by the lever b^6 .

As above indicated, my invention may be embodied in a machine adapted for punching instead of shearing, suitable punching-dies being substituted for the shear blades or 85 members here shown.

For the sake of convenience, I have referred in some of the following claims to the lever b as a carrier and to the lever b^4 (shown in Fig. 5) as a primary operating-lever. 90

In Figs. 6 and 7 I show the cam-head d provided with a cam-shaped groove d^5 , which receives a stud d^6 on an arm d^7 , affixed to the lever b . Said cam is formed to impart up-and-down movements to the lever b through 95 the arm d^7 , and to hold the lever b at all times in operative bearing against the cam-head. This arrangement is more positive and reliable than the spring g . (Shown in Figs. 1 and 2.)

In Figs. 6 and 7 I show also a guard or rest e^5 , composed of an angular bar, the lower end of which is bent inwardly and secured to the bottom of the frame by means of a block e^6 , secured by a bolt e^7 to the frame a . By loosening the bolt e^7 the rest e^5 can be released and removed from the machine. 105

I claim—

1. In a machine of the character specified, the combination of a supporting-frame having a fixed shear-blade; a lever pivoted at one end to said frame and carrying a shear-blade adapted to coöperate with that on the supporting-frame; and a cam-head pivoted to the supporting-frame, arranged to bear on the swinging end of the lever, and having two interchangeably-operative differentiated cam-surfaces and a median surface nearest the pivot, whereby movement of the cam-head from a position where said median surface 110 engages the lever may operate to engage either cam-surface with the lever, each cam-surface having a sufficient total rise to bring the shear-blades together but so differentiated 115 that one brings said blades together through a greater portion of their length than the other under the same extent of movement of the cam-head, substantially as and for the purpose described. 120

2. In a machine of the character specified, the combination of a supporting-frame having a fixed cutting member, a lever pivoted 125

at one end to said frame and carrying a cutting member adapted to coöperate with the fixed member, a cam-head pivoted to the supporting-frame, arranged to bear on the swinging end of the lever and having two interchangeably-operating cam-surfaces with a median surface nearest the pivot whereby movement of the cam-head from a position where said median surface engages the lever 5 may operate to engage either cam-surface with the lever, said cam-head having a cam-shaped groove in one side the converse of the exterior cam-surfaces with relation to the

pivot of the head; an arm fastened to the lever and engaging the cam-groove on the 15 upper side of the pivot; and an operating arm or lever on the cam-head.

In testimony whereof I have signed my name to this specification, in the presence of two subscribing witnesses, this 19th day of 20 February, A. D. 1895.

JARED B. McLANE.
